(74) Attorney, Agent, or Firm—G. Donald Weber, Jr.

(57) **CLAIM**

The ornamental design for an automotive wheel, as shown and described.

DESCRIPTION

FIG. 1 is a perspective view of the automotive wheel of the instant invention; and,

FIG. 2 is a side elevation view of the automotive wheel of the instant invention.

The broken line showing of environment is for illustrative purposes only and forms no part of the claimed design.
